(57) **CLAIM**

The ornamental design for a portable air purifier, as shown and described.

DESCRIPTION

1. Portable air purifier

1.1 : Perspective

1.2 : Front

1.3 : Back

1.4 : Left

1.5 : Top

1.6 : Bottom

1.7 : Exploded

The broken lines depict portions of the portable air purifier that form no part of the claimed design; reproduction 1.1 is a front perspective view of the portable air purifier; reproduction 1.2 is a front view thereof; reproduction 1.3 is a back view thereof; reproduction 1.4 is a left view thereof where the right view is a mirror image; reproduction 1.5 is a top view thereof; reproduction 1.6 is a bottom view thereof; reproduction 1.7 is an exploded front view thereof; this is a design for a portable air purifier which can be attached to the

(Continued)

window, etc. by its suction plate at the bottom part; as you can see in reproduction 1.7, the main body of the air purifier can be detached and used separately from the suction plate at the bottom part.
